Des. 238,629

Patented Feb. 3, 1976

238,629

DOUBLE HANDCUFF CASE

Paul E. Tibbetts, Chula Vista, Calif.
(2920 Ares Way, San Diego, Calif. 92139)

Filed Aug. 2, 1974, Ser. No. 494,199

Term of patent 14 years

Int. Cl. D2—07

U.S. Cl. D2—400

FIG. 2

FIG. 1

FIG. 3

FIG. 4

FIG. 1 is a front perspective view of a double handcuff case showing my new design;

FIG. 2 is a rear elevational view thereof;

FIG. 3 is a front perspective view thereof in an open position;

FIG. 4 is a front elevational view thereof in an open position.

I claim:

The ornamental design for a double handcuff case, as shown and described.
